UNITED STATES PATENT OFFICE.

HORACE BUTLER, OF LUDINGTON, MICHIGAN.

SKIDDING-MACHINE.

SPECIFICATION forming part of Letters Patent No. 288,306, dated November 13, 1883.
Application filed June 18, 1883. (No model.)

To all whom it may concern:

Be it known that I, HORACE BUTLER, a citizen of the United States, residing at Ludington, in the county of Mason and State of Michigan, have invented certain new and useful Improvements in Skidding-Machines, of which the following is a specification, to wit:

This invention relates to an improvement in machines for skidding logs; and it consists in the combination, with a truck carrying a mast, engine, and suitable drums provided with clutches, of a series of guy-ropes, a traveling sheave-carriage, and a drag-rope having devices for attachment to the logs, substantially as will be hereinafter more fully set forth.

In order to enable others skilled in the art to which my invention appertains to avail themselves of its benefits, I will now proceed to describe its construction and operation, referring to the accompanying drawings, in which—

Figure 1 is a side elevation of my invention; Fig. 2, a plan view of the same, and Fig. 3 a cross-section of the device for operating the traveling sheave-frame.

A represents a truck or platform, which is preferably supported upon wheels, to facilitate moving from place to place. This truck is provided with a steam-boiler, B, and one or more steam-cylinders, B', the pistons of which are connected to crank-pins *b* upon the ends of a shaft, *b'*, journaled in raised portions of the main frame, and provided with a suitable spur-pinion, *b²*, as shown. The spur-pinion *b²* meshes with a spur-wheel, *c*, fast upon a shaft, *c'*, journaled in the frame, and carrying a loose winding-drum, C, as represented in Fig. 2. The pinion *b²* also meshes with and gives motion to a second spur-wheel, *d*, upon a shaft, *d'*, carrying a loose winding-drum, D, and the gear *d* in turn meshes with and contributes motion to a pinion, *e*, upon a shaft, *e'*, also having a loose winding-drum, E, and just above this latter drum is journaled in the frame a small shaft, *E'*, set at a slight incline, the purpose of which will be presently seen. All the shafts *c'*, *d'*, and *e'* are arranged to have a slight endwise motion by means of a quick-screw, *c²* *d²* *e²*, having crank-handles, as shown, and the spurs and pinions *c* *d* *e* are formed on their inner faces with clutches

c³ *d³* *e³*, respectively, which, when the shafts are shifted, are engaged or disengaged with the respective winding-drums, and admit of either or all of them being operated at the will of the attendant. Upon one end of the truck A is placed a pole or mast, F, from the top of which extend guy ropes or rods *f* *f*, of any suitable material, secured at their outer ends to stumps, trees, or stakes driven into the ground. Upon one of these guys *f* *f* is placed a frame or carriage, G, provided with two grooved rollers or pulleys, *g* *g*, by which it travels upon the guy, and having a block, G', depending from its lower end. To the inner side of the traveling carriage G is secured the end of a hauling-line, *g'*, which passes over a sheave, *g²*, at the mast-head, and is then passed down and several times around the drum E and shaft E', then led again through the sheave-block at the mast-head, through a leading-sheave, *g³*, upon the side of the traveler, and out to the end of the guy *f*, where it is rove through a block, *g⁴*, and carried back to the traveler, where it is secured.

75

To the drum C is secured one end of a skidding-line, *h*, the other end of which is rove through the sheave-block *g²*, through the block G', and is provided with a pair of dogs or tongs, H, for attachment to a log. The device is especially designed for cleaning land and hauling logs to a central point, where they may be sawed or loaded upon cars, trucks, or sleighs by the machine and drawn to the desired point. The skidding-line *h* is carried out and attached to a log, while the traveler is drawn out upon the guy as far as may be required. The engine being now started, the drums are revolved, and the skid-line and traveler are brought in at the same time. Should a rock or stump or other obstruction be in the way, the drum E is unclutched and the traveler allowed to remain at rest, while, the skid-line being still reeled in, the end of the log is lifted till clear of the obstruction, when, the traveler being again started, the log is dragged over the obstacle and soon brought to the machine. It will thus be seen that the entire management of the log is under the control of the operator at the engine, and he can at any time start or stop any or all of the machinery, as may be required for the proper handling of the timber.

It is obvious that either a block with three sheaves, as shown in the drawings, or three single blocks, may be used at the mast-head for leading the lines, and any desired kind of clutch or gearing may be used upon the shafts, as may be found most desirable. By shifting the traveler from one guy to another a large area of ground may be cleared without changing the position of the trucks. The shaft E' 5 being set on an incline prevents the fouling of the line as it passes around it and the drum E.

Having thus fully described my invention, what I claim as new, and desire to secure by Letters Patent, is—

- 15 1. In a log-skidding machine, a truck or platform carrying suitable winding-drums, a device for giving motion to the same, and a mast guyed out to suitable points, in combination with a traveler upon one of the guys, having a line to haul it in and out connected to the winding devices, and a skidding-line carried by the traveler, and also connected to the winding mechanism, substantially as shown and described.
- 20 2. In a log-skidding device, a truck or platform carrying an engine and boiler, a series of winding-drums loose upon shafts, and connected thereto by means of clutches, a series of gears and pinions by which said shafts are connected, a mast provided with leading-sheaves, and a series of guy rods or ropes car-

ried out in different directions and secured to trees or stumps, in combination with a traveler having grooved pulleys adapted to run upon the guys, a leading-block upon one side 35 and another suspended below, and a hauling-rope rove over the sheaves at the mast-head and around one of the drums, whereby the traveler is hauled in or out, and a skidding-rope provided with means for attachment to 40 a log, and rove through a block upon the traveler, a sheave at the mast-head, and secured to one of the winding-drums, substantially as shown and described.

3. In a log-skidding machine, the traveler G, 45 adapted to travel upon one of the guys, and provided with the leading-blocks g' G', and the hauling-line g', rove substantially as herein described, in combination with the clutch-drum E and shaft E', set upon an incline, around 50 both of which it is passed several times, whereby the traveler is hauled out or in at the will of the operator, and the line is prevented from fouling in passing around the drum and shaft, as shown and described.

In testimony whereof I affix my signature in presence of two witnesses.

HORACE BUTLER.

Witnesses:

P. H. HALL,
J. B. McMAHON.

Affidavit having been filed in the Patent Office showing that the name of the patentee of Letters Patent No. 288,306, granted November 13, 1883, for an improvement in "Skidding Machines," should have been written and printed *Horace Butters* instead of "Horace Butler;" it is hereby certified that the said patent should be read with this correction therein to make the same conform to the record of the case in the Patent Office.

Signed, countersigned, and sealed this 8th day of January, A. D. 1884.

[SEAL.]

M. L. JOSLYN,
Acting Secretary of the Interior.
